LOUIS STEINBERGER, OF BROOKLYN, NEW YORK.

SCOOL-TYPE-DISK STRAIN-INSULATOR.

1,166,394.

Specification of Letters Patent. Patented Dec. 28, 1915.

Application filed August 7, 1912. Serial No. 718,789.

To all whom it may concern:

Be it known that I, Louis Steinberger, residing at Brooklyn, Kings county, New York, N. Y., have invented certain new and useful Improvements in Spool-Type-Disk Strain-Insulators, of which the following is a specification.

This invention relates to an insulator comprising a plurality of concatenated units suspended in vertical column and flexibly connected together, and adapted to support a conductor from the lowest unit in the column, the units being preferably arranged so that the vertical planes of the axes of the alternate units will stand in right-angular relation, whereby to increase the insulating value by the addition of one or more units to the column.

Among the several objects of the invention may be specifically enumerated the following: I. To improve the general form of units for insulators of this class. II. To provide an efficient insulator of the class described, comprising units of few parts and of easily and cheaply manufactured design. III. To form the units of such shape as to be of a very high dielectric value and of considerable mechanical strength. IV. To so form the independent units that, in their angular disposition relatively to each other, each alternate unit will present a differently protected surface to any one side of the column and thereby interpose numerous differently shaped surfaces, some of which will be bound to remain dry in the presence of rain, sleet, etc. V. To provide an insulator unit comprising a body portion having a conductor extending therethrough, and adapted for use in supporting the unit, and having a second conductor surrounding the first conductor and insulated therefrom by said body, the body having formations adapted to prevent the ready passage of moisture over its surface toward either of said conductors. VI. To provide an insulator comprising a body portion having conductor parts at its opposite ends and having a conductor part enclosing its intermediate portion, to provide annular enlargements upon said body between the intermediate conductor part and the end conductor parts, and to provide means upon the op-

posing surfaces of said enlargements for preventing a flow of liquid therealong toward the intermediate conductor part.

55

Other objects and aims of the invention, more or less broad than those stated above, together with the advantages inherent, will be in part obvious and in part specifically referred to in the course of the following description, and the scope of protection contemplated will appear in the claims.

60

In the accompanying drawings, which are to be taken as a part of this specification, and in which I have shown a merely illustrative form of embodiment of the invention: Figure 1 is a side elevational view, partly in section, of a column of units arranged to form a flexible insulator embodying the principles of this invention; and Fig. 2 is a transverse sectional view, partly in elevation, of one of the units illustrated in Fig. 1.

65

Referring to the drawings by numerals, 1, 2 and 3 indicate generally three units which have been chosen as sufficient to illustrate the principles of this invention. These units are preferably identical in size and shape, and each comprises a rod 4 of conducting material arranged horizontally, and preferably having detachable heads 5 at its opposite ends, which heads are threaded or otherwise adjustably secured upon the end portions of the rod. A yoke or bail 6 has its opposite ends depending and apertured as at 7, and the end portions of the rod 4 extend through said apertures, so that the rod 4 is supported by the bail. This bail is so formed with respect to the insulator as to be spaced a considerable distance therefrom intermediate its length in order to minimize the danger of the current arcing across. Intermediate its ends the bail is formed with a lug 8, apertured as at 9, and adapted to receive a bolt 10 for supporting the bail, either from a superposed unit or from any other suitable support, as for instance, the fixed suspension 11.

90

Fixed concentrically upon the rod 4, intermediate the ends of the bail 6, is a cylindrical body 12 of insulating material, said body having axial extensions 13 projecting from its opposite ends, the body and the extensions being apertured or made tubular

100

for the reception of the rod 4, and the outer end faces of the extensions being engaged by the inner faces of the end portions of the bail, and the heads 5 clamping said bail ends rigidly in place. At the opposite ends of the body 12 are formed disks 12' each of which is provided with a plurality of axially arranged ridges 14, 15 and 16, disposed about the extensions 13, the ridge 14 being of relatively large cross-section and projecting for a relatively greater distance from said disks than the ridges 15 and 16 which are of successively reduced proportions. The ridge 14 is closest about the extension 13, and the ridges 15 and 16 are spaced concentrically between the ridge 14 and the outer annular edge 17 of the disks. The outer edge of the ridge 14 is thus nearest the outer end surface of the adjacent extension 13, and the outer edges of the ridges 15 and 16, and the annular edge 17 of the body 12, recede, preferably uniformly, from the vertical plane of the outer edge of the ridge 14, so as to maintain a considerable distance between all parts of the insulating member and the adjacent inner surface portions of the bail 6 without the necessity for forming a decided bulge in the bail.

Intermediate its ends the annular surface of the body portion 12 is considerably reduced and forms an annular seat 18 for the encircling band 19 of conducting material, which band forms a support either for the next adjacent unit below or for the supported line wire. The walls defining the reduced portion 18 preferably are arranged at an incline extending from the annular edges of said reduced portion substantially to the annular edges 17 of the disks, so that practically the whole annular surface of the insulator inclines toward the member 19 and produces the flange-like parts or disks on said body extending beyond the seat 18. The opposing walls or surfaces of the disks, which would naturally conduct liquid directly to the member 19 are formed, however, with means adapted effectually to prevent such a flow, said means comprising preferably a series of radially projecting, annular, concentric ridges 20, which are preferably of relatively small cross-section. These ridges provide decided annular depressions 21, forming conducting paths about the walls, along which liquid, intercepted by the ridges, flows to the lower side of the body and drips therefrom, not having been allowed to come into contact with any metallic portion of the unit.

It has been an important object of this invention to maintain the metallic parts of the structure in as simple and inexpensive design as possible and to form the insulating member of each unit of integral construction so shaped as to be readily molded, but comprising parts carefully arranged to effec-

tively prevent the flow of liquid between the metallic parts comprising the two conductors of the unit, and at the same time materially and effectively increase the surface distance between the units. The formation 70 is also such as to present decidedly different shapes of moisture resisting surfaces at any one side of the column and thus to provide, more effectually, moisture proof parts intermediate the upper and lower ends of the 75 column.

The bands 19 are preferably divided and detachably connected together by suitable screws 22 extending through outstanding lugs 23 formed on the adjacent end portions 80 thereof, so that the band may be readily attached and detached at will. The bands intended to support a suspended unit, have their lower section formed with a lug 24, apertured as at 25, and adapted to receive 85 one of the bolts 10. For the lowest unit in the column the lug is preferably formed with a threaded aperture adapted to receive the upper end of a rod or link 26 which depends from said unit into threaded engagement with a lug 27 formed upon a clamp 28, the clamp, in turn, engaging and directly supporting the conductor wire 29.

As many changes could be made in this construction without departing from the 90 scope of the following claims, it is intended that all matter contained in the above description or shown in the accompanying drawing shall be interpreted as illustrative only and not in a limiting sense.

Having thus described my invention, what I claim as new and desire to secure by Letters Patent, is:

1. An insulator comprising a cylindrical body having a relatively reduced annular portion intermediate its length formed between opposingly disposed annular walls which flare abruptly outwardly from said annular reduced portion, and said walls having each an annular ridge thereon between 105 its outer periphery and said annular reduced portion, adapted to form annular grooves about said walls for intercepting the flow of liquid along said walls toward said relatively reduced portion and conducting 110 said liquid off of the insulator at a point removed from said annular reduced portion.

2. An insulator comprising a cylindrical body disposed horizontally, having a relatively reduced annular portion intermediate 120 its ends formed between conically shaped walls, flaring abruptly outwardly from said annular reduced portion and inclining in all radial directions toward said annular reduced portion, and each of said walls being formed with a plurality of annular substantially concentric ridges extending radially therefrom at spaced intervals between the outer peripheries of said walls and said annular reduced portion in planes substan- 125

tially at right angles to the longitudinal axis of the insulator, said ridges being of successively increasing diameters from said reduced annular portion outwardly, so as to provide a plurality of annular grooves on said walls between them adapted to intercept the flow of moisture along said walls toward said annular reduced portion, and to conduct said moisture off of the under

side of the insulator at a point removed 10 from said annular reduced portion.

In testimony whereof, I affix my signature in the presence of two witnesses.

LOUIS STEINBERGER.
